INFANT SAFETY CAR SEAT

Edward D. Levy, Spring Valley, N.Y., assignor to Union Carbide Corporation, a corporation of New York

Filed Apr. 16, 1965, Ser. No. 84,817

Term of patent 14 years

(Cl. D15—1)

FIG. 4

FIG. 5

FIG. 1 is a front perspective view of a car seat embodying my design with strap means being shown in broken lines for the purpose of illustration;

FIG. 2 is a side elevational view with strap means partially broken away for convenience of illustration;

FIG. 3 is a top view with strap means partially broken away for convenience of illustration;

FIG. 4 is a rear elevational view thereof; and

FIG. 5 is a bottom view with strap means partially broken away for convenience of illustration.

The dominant features of my design reside in those portions shown in full lines on the drawing.

The inverted U-shaped anchoring hooks shown in FIGURE 1 are for illustrative purposes only.

I claim:

The ornamental design for an infant safety car seat, as shown and described.
